Primary Examiner — Richard Edgar*Assistant Examiner* — Jessica Ruth Grable(74) *Attorney, Agent, or Firm* — The Belles Group, P.C.(57) **CLAIM**

The ornamental design for a bed frame, as shown and described.

DESCRIPTION

FIG. 1 is a top, front perspective view of a bed frame showing our new design;

FIG. 2 is a rear perspective view thereof;

FIG. 3 is a bottom, front perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines illustrate portions of the bed frame that form no part of the claimed design.

1 Claim, 8 Drawing Sheets(56)
